COMBINATION FISH SKINNING AND SCALING TOOL OR THE LIKE

Admiral D. Henry, 8108 Cantrell Road, and Max Henry Ezell, 1108 Battery St., both of Little Rock, Ark.

Filed Sept. 7, 1962, Ser. No. 71,592

Term of patent 14 years

(Cl. D31—4)

FIGURE 1 is a side elevational view of a combination fish skinning and scaling tool or the like, showing our new design;

FIGURE 2 is a top plan view thereof;

FIGURE 3 is a bottom plan view of the same;

FIGURE 4 is a side elevational view, looking toward the opposite side of the tool and showing the tool in an open position;

FIGURE 5 is an enlarged end elevational view thereof, looking from left to right of FIGURE 1, and

FIGURE 6 is an enlarged cross sectional view taken on the line 6—6 of FIGURE 1, looking in the direction of the arrows.

I claim:

The ornamental design for a combination fish skinning and scaling tool or the like, substantially as shown.
